UNITED STATES PATENT OFFICE.

WALTER S. BRIDGES, OF CHICAGO, ILLINOIS.

FAUCET.

1,181,368.

Specification of Letters Patent. Patented May 2, 1916.

Application filed May 26, 1915. Serial No. 30,579.

To all whom it may concern:

Be it known that I, WALTER S. BRIDGES, a citizen of the United States, residing at Chicago, in the county of Cook and State 5 of Illinois, have invented certain new and useful Improvements in Faucets, of which the following is a specification.

This invention relates to faucets which are designed to deliver hot and cold water, 10 or a mixture of both, and its object is to provide a faucet of this kind which is very simple in construction, and which can be operated to supply water to two adjacent basins, tubs or other receptacles, by mounting the faucet therebetween.

The invention also has for its object to provide a faucet which is not liable to leakage and which requires no packing washers or similar devices.

20 The objects stated are attained by means of a novel combination and arrangement of parts to be hereinafter described and claimed, and in order that the invention may be better understood, reference is had 25 to the accompanying drawing in which—

Figure 1 is a vertical section of the faucet, and Fig. 2 is a horizontal section on the line 2—2 of Fig. 1.

Referring specifically to the drawing, 30 5 denotes the casing or barrel of the faucet, the same being cylindrical and having in its side two inlet ports 6 and 7, respectively, which have suitable supply connections 8 and 9, respectively. One of these ports is 35 for hot water and the other for cold water. The casing is closed at the bottom, and to its upper end is applied a removable closure in the form of a screw plug 10.

In the casing 5 is rotatably mounted a 40 cylindrical valve 11 which seats between the closed end of the casing and the screw plug 10. The end of the valve cylinder which seats on the closed end or bottom of the casing is open, and its opposite end has 45 a wall 12 closing said end. From this wall 12 extends inward a tube 13 which is located centrally within the valve cylinder and extends down as far as the open end thereof to seat against the bottom of the valve casing, this end of the tube, however, being closed. The tube 13 is integral with the 50 wall 12, and from the latter also extends outward a tube 14 which is in line with and communicates with the tube 13. The plug 10 has a central opening through which the tube 14 extends, and on the outside of the

plug said tube has an outlet spout 15. The valve cylinder 11, its wall 12, and the tubes 13 and 14 are all integral.

From the bottom of the valve casing 5 60 rises an integral annular wall 16 which fits in the space between the inside of the valve cylinder 11 and the outside of the tube 13. This wall extends to the end wall 12 and is in contact at its upper end with the inner 65 surface of said wall.

The valve cylinder 11 and the tube 13 have ports 17 and 18, respectively, said ports being in alinement and in the plane of the inlet ports 6 and 7. The wall 16 has a 70 port 19 located between the ports 17 and 18 and in communication with both of said ports. The port 19 is wider than the port 17 so that the latter port will remain in communication with the former when the 75 valve is rotated to bring said port opposite either inlet port. The valve cylinder also has a port 20 which is diametrically opposite the port 17, and the tube 13 has a corresponding port 21. This arrangement of 80 double ports enables the valve to be used to supply two basins, laundry tubs or other receptacles, 22 and 23, respectively, the valve being mounted therebetween. When the valve is in the full line position shown 85 in Fig. 1, the basin 22 will be supplied if the valve is turned to bring the port 17 into registry with the inlet ports 6 or 7, the flow being through the ports 17, 19, and 18, and from the latter into the tube 13 and out of 90 15. Upon swinging the valve to the dotted position shown in Fig. 1, the ports 20 and 21 are brought opposite the inlet ports and the port 19, and a hot or cold water supply may 95 be obtained by properly turning the valve to bring the port 20 into registry with the required inlet port. A mixture of hot and cold water can also be obtained for either basin by bringing the valve ports to a position 100 where they partly lap both inlet ports. The valve structure, with the wall 16, effectually prevent leakage, and packings, washers or similar devices are not required.

While the preferred embodiment of the invention has been shown, it will be evident that various modifications may be made without a departure from the spirit or scope of the invention as claimed hereinafter. Thus, the number of ports may be increased 110 if additional basins or tubs are to be supplied.

I claim:

1. A faucet comprising a casing closed at one end and having a side inlet, a closure for the other end of the casing, a rotatable cylindrical valve in the casing, said valve being open at one end and said end seating on the closed end of the casing, a wall closing the other end of the valve and seating against the aforesaid casing closure, communicating tubes extending from opposite sides of the aforesaid wall, one of said tubes passing through the casing closure and having an outlet, and the other tube extending into the casing and being surrounded by the valve, the outer end of the last-mentioned tube being closed and seating on the closed end of the casing, a wall extending from the closed end of the casing into the space between the inside of the valve and the outside of the last-mentioned tube, and to the first-mentioned wall, ports in the valve and the second-mentioned tube, the valve port being in the plane of the casing inlet, and a port in the second-mentioned wall, said port being in communication with the ports of the valve and the second-mentioned tube.
2. A faucet comprising a casing closed at one end and having side inlets, a closure for the other end of the casing, a rotatable cylindrical valve in the casing, said valve being open at one end and said end seating on the closed end of the casing, a wall closing the other end of the valve and seating against the aforesaid casing closure, communicating tubes extending from opposite sides of the aforesaid wall, one of said tubes passing through the casing closure and having an outlet, and the other tube extending into the casing and being surrounded by the valve, the outer end of the last-mentioned tube being closed and seating on the closed end of the casing, a wall extending from the closed end of the casing into the space between the inside of the valve and the outside of the last-mentioned tube, and to the first-mentioned wall, ports in the valve and the second-mentioned tube, the valve port being in the plane of the casing inlet, and a port in the second-mentioned wall, said port being in communication with the ports of the valve and the second-mentioned tube, and its width being greater than the valve port to lap said port in either position relative to the casing inlets.
3. A faucet comprising a casing provided with an inlet and having an annular wall spaced from its side, said wall having a port, a cylindrical rotatable valve in the casing

on the outside of the annular wall, said valve having a port in the plane of the casing inlet and the port of the wall, a tube extending inward from the valve and surrounded by the annular wall, said tube having a port in the plane of the port of said wall, and an outlet tube on the valve in communication with the aforesaid tube.

4. A faucet comprising a casing provided with inlets and having an annular wall spaced from its side, said wall having a port, a cylindrical rotatable valve in the casing on the outside of the annular wall, said valve having a port in the plane of the casing inlet and the port of the wall, a tube extending inward from the valve and surrounded by the annular wall, said tube having a port in the plane of the port of said wall, and an outlet tube on the valve in communication with the aforesaid tube, the width of the aforesaid wall port being greater than the valve port to lap said port in either position relative to the casing inlets.

5. A faucet comprising a casing provided with an inlet and having an annular wall spaced from its side, said wall having a port, a cylindrical rotatable valve in the casing on the outside of the annular wall, said valve having diametrically opposite ports in the plane of the casing inlet and the port of the wall, a tube extending inward from the valve and surrounded by the annular wall, said tube having diametrically opposite ports in the plane of the port of said wall, and an outlet tube on the valve in communication with the aforesaid tube.

6. A faucet comprising a casing provided with inlets and having an annular wall spaced from its side, said wall having a port, a cylindrical rotatable valve in the casing on the outside of the annular wall, said valve having diametrically opposite ports in the plane of the casing inlet and the port of the wall, a tube extending inward from the valve and surrounded by the annular wall, said tube having diametrically opposite ports in the plane of the port of said wall, and an outlet tube on the valve in communication with the aforesaid tube, the width of the aforesaid wall port being greater than the valve port to lap said port in either position relative to the casing inlets.

In testimony whereof I affix my signature in presence of two witnesses.
